(57) **CLAIM**

The ornamental design for a fixture element, as shown and described.

DESCRIPTION

FIG. 1 is a front, bottom perspective view of a fixture element according to our new design;

FIG. 2 is a bottom plan view thereof;

FIG. 3 is a front elevational view thereof, the rear elevational view thereof being a mirror image of the front side shown;

FIG. 4 is a left side elevational view thereof, the right side elevational view thereof being a mirror image of the left side shown; and,

FIG. 5 is a top plan view thereof.

The broken line representations in the figures are for the purpose of illustration only, and form no part of the claimed design.

In a preferred embodiment, the nature of this product is a fixture element in the form of a wall-mounted light.
